UNITED STATES PATENT OFFICE.

FRANK L. HARMON, OF BEVERLY, MASSACHUSETTS.

MACHINE FOR SKIVING AND FOLDING LEATHER.

SPECIFICATION forming part of Letters Patent No. 731,566, dated June 23, 1903.

Application filed October 2, 1899. Serial No. 732,316. (No model.)

To all whom it may concern:

Be it known that I, FRANK L. HARMON, residing at Beverly, in the county of Essex and Commonwealth of Massachusetts, have invented a new and useful Machine for Skiving and Folding Leather, of which the following is a specification, reference being had to the accompanying drawings.

The object of this invention is to produce a folded edge of a piece of leather which is of about the same thickness as the piece of leather before it is folded; but the nature of this invention, exclusive of function which is not a part of said nature, cannot be briefly and comprehensively disclosed without conveying ideas as follows in language substantially as follows: a skiving-knife adapted to skive or bevel a piece of leather near the edge of said leather; means whereupon said skiving-knife may be actuated; a feeding device adapted to move said leather a distance of about one-eighth of an inch toward said skiving-knife in order that said leather may be skived or beveled as far as said feeding device is adapted to move said leather; means whereupon said feeding device may be actuated; a slitting device adapted to cut a slit about one-eighth of an inch long in the skived or beveled part, provided it be formed at about right angles to the skived or beveled part and in such a place that a part of the skived or beveled part near the thinnest edge of said skived or beveled part may be adapted to be bent downward without bending any other part of the leather downward; means whereupon said slitting device may be actuated; a beveled and recessed device adapted to fold the part of said skived part adapted to be bent downward, provided it be formed and bent downward, and adapted to rub the skived and bent part from the folded edge inward, provided said part be formed, bent, and folded; means whereupon said folding and rubbing device may be moved in such a direction as to fold the part of said skived part adapted to be bent downward, if said part be formed and bent downward, in a direction from the skived edge inward and rubs said part of the skived part adapted to be bent downward in a direction from the folded edge inward, if said part be formed, bent, and folded; a receptacle adapted to hold cement; means whereupon a proper amount of cement may

be automatically taken out of said receptacle and deposited upon a recessed part of said device adapted to fold and rub; a device adapted to bend said part of said skived part adapted to be bent downward and press it down upon a recessed part of said device adapted to fold and rub in order that cement upon said recessed part may be rubbed upon said skived part by said device adapted to fold and rub and also adapted to bend said part of said skived part adapted to be bent downward into a recessed part of said device adapted to fold and rub in order that said part of said skived part adapted to be bent downward may be folded by said device adapted to fold and rub and that the opposite side of said part of said skived part adapted to be bent downward from the side on which cement is deposited, provided said skived part be bent and folded, may be rubbed by said device adapted to fold and rub; means adapted to heat said device adapted to fold and rub to facilitate the folding of said part of said skived part adapted to be bent downward and also to quicken the drying of the cement applied to said skived part; in combination with a grinding device adapted to grind said skiving-knife whereupon said leather may be skived or beveled, and means whereupon said grinding device may be forced to grind said skiving-knife.

A machine in which this invention is embodied is comprehensively shown in the accompanying drawings, and the especial features and novel mechanical combinations of parts shown therein will be hereinafter fully described and set forth, and claimed in the claims appended hereto.

In the accompanying drawings, Figure 1 is a top plan view of the machine embodying this invention. Fig. 2 shows a cross-sectional elevation on line $x-x$, indicated by an arrow at the left-hand corner of Fig. 1. Fig. 3 shows a longitudinal sectional elevation on line $y-y$, indicated also by an arrow at the left-hand corner of Fig. 1. Fig. 4 is a perspective detail view of a feeding device; and Figs. 5, 6, 7, and 8 show perspective detail views of devices whereupon the feeding device is yieldingly supported and whereupon the feeding device may be manually adjusted or moved and secured at any necessary angle to the

cutting edge of a rotatory disk skiving-knife, leaving the feeding device operative, thereby operatively holding the part of the feeding device which moves the leather at any necessary angle to the rotatory disk skiving-knife, so that the piece of leather may be skived at the edge of said leather at any necessary angle. Fig. 9 shows a vertical section of a device by which a piece of leather is folded, so as to form a folded edge, and is rubbed in a direction inward from said folded edge in operative connection with a part of a cement-receptacle and devices connected therewith, whereupon a proper amount of cement is in practice taken out of said cement-receptacle. Fig. 10 shows the construction of a rod and a sleeve thereon whereupon the feeding device is moved in practice. Fig. 11 shows a vertical section of a wheel whereupon a grinding device is rotated in practice for grinding a rotatory disk skiving-knife. Fig. 12 is a perspective view of a gas-burner for heating the device for rubbing the folded part of a piece of leather in a direction inward from the folded edge. Fig. 13 shows a perspective view of a cement-receptacle and devices connected therewith, whereupon a specific or proper amount of cement is in practice automatically taken out of said cement-receptacle. Ascertain parts by which cement is automatically deposited upon a device for rubbing the cement upon the skived part of the leather after the cement is automatically taken out of said cement-receptacle are obscured by many lines in Fig. 1, a detail plan of said parts is shown in Fig. 14, free from obscuring lines, in order that a comprehensive idea may be conveyed as to their construction and operation. Fig. 15 is a sectional detail in side elevation, free from obscuring lines, to more fully illustrate the parts shown in Figs. 3, 1, and 14. Fig. 16 shows an end elevation of some of the parts shown in detail in Figs. 14 and 15 and also illustrates more fully than other views how that a cover for covering the device for rubbing the cement upon the leather is secured to the frame of the machine. Fig. 17 is a sectional detail view in elevation to illustrate the construction of a brush or device for depositing the cement upon the device for rubbing it upon the skived part of the leather.

In the journal-bearings of the knife-shaft support A²², (shown in Figs. 1, 2, and 3,) rigidly but adjustably secured to the frame A², as and for the purpose hereinafter described, the rotatory disk skiving-knife shaft A²⁰ (shown in Figs. 3 and 2) is journaled. The horizontal grooved wheel A²¹ (shown in Figs. 3 and 2) is secured upon said rotatory disk skiving-knife shaft A²⁰. A round belt (not shown) operating in practice in the groove of the wheel A²¹ rotates said wheel A²¹, the rotatory disk skiving-knife shaft A²⁰, secured thereto, and the rotatory disk skiving-knife A¹⁷, secured to said shaft, with great rapidity. Attention is called to the fact that the power

conveyed by this belt is exclusively applied to said wheel, knife-shaft and knife, or, in other words, the knife-shaft is thereby operated independent of the means for conveying power to other parts of the machine. Said wheel, knife-shaft and knife are rotated independent of the power conveyed to the other parts of the machine, which comprise devices whereupon feeding, cementing, slitting, folding, heating, and rubbing are accomplished in order that it may be possible to raise the speed of the wheel A²¹, knife-shaft A²⁰, and knife A¹⁷ to any desired speed from its normal speed to facilitate the skiving of some kinds of leather properly without affecting the speed of the rest of the operative devices of the machine, and a construction whereupon this could be accomplished not having been heretofore made the combination of means for rotating the knife-shaft and skiving-knife independent of the power conveyed to other operative parts of a skiving-machine in combination with the other operative parts of a skiving-machine in order that the speed of the knife may be raised without affecting the speed of the other operative parts of the machine is of my invention.

On the left-hand side of the frame or box A², (shown in section in Fig. 3,) which box incloses the greater part of the operative mechanism of the machine, is the bracket A', secured to the frame or box A² on the outside of the frame or box by two screws, one above the other, and said bracket extends toward the left at right angles to the frame or box A² outside of the frame. This bracket is peculiar in shape, the lower end thereof being the journal-bearing shown inside of the frame or box A² near the left-hand lower corner of Fig. 3, in which journal-bearing the shaft A is journaled, and the upper end of said bracket being the journal-bearing directly above the first-named journal-bearing, also inside of the frame or box A², in which last-named journal-bearing the shaft A is also journaled. Upon the top of the shaft A, above the last-named journal-bearing, the device A⁴ for folding and rubbing the skived part of the leather is rigidly secured and is rotated in practice with said shaft. This device A⁴ is shaped like a disk and is beveled, as is shown in Fig. 9, in which figure the device A⁴ is shown in vertical section. Attention is called to the left-hand side of Fig. 1, to the outer circular line which describes the circumference of said device A⁴, in order that a comprehensive idea of the size of this device may be conveyed. Attention is also called to the left-hand upper corner of Fig. 2, at which place in said figure the device A⁴, shown in elevation, is not obscured by lines, and attention is also called to the right-hand lower corner of Fig. 14, where the device A⁴ is shown in plan, free from obscuring lines, and attention is also called to the right-hand upper corner of Fig. 15, in which figure the device A⁴ is shown in section and is also shown se-

cured to a part of the shaft A. Attention is again called to the left-hand side of Fig. 3, where the horizontal grooved wheel A³ is shown secured to the shaft A. A round belt 5 (not shown) operating in practice in the groove of said wheel A³ rotates said wheel A³, the shaft A, shown secured thereto, and the device A⁴ shown secured to said shaft and for folding and rubbing the skived part of a 10 piece of leather, and to which device attention has been called in the several views.

Upon the shaft A, inside of the frame or box A² at the left-hand lower corner of said frame, the eccentric or cam A⁵ is shown rigidly secured to the shaft A, which eccentric or cam is rotated by the shaft A when the shaft A is rotated. Immediately above said eccentric or cam A⁵ is shown the coil-spring A⁹, one end of which is secured to a screw 15 shown fast in the bracket A' and the other end of which is secured to a screw shown fast in the sleeve A¹², which sleeve is shown fast to the rod A⁶, which sleeve and rod are shown in detail in Fig. 10 shown below Fig. 3, and 20 as said rod A⁶ is movably supported in the slideways A⁷ and A⁸, fast to the lower part of the frame A², the coil-spring A⁹ moves said rod in practice and forces the left-hand end of said rod (shown also in Fig. 10) against the 25 cam or eccentric A⁵. Therefore it is plain that the rod A⁶ is moved in practice toward the right in the slideways A⁷ and A⁸ against the stress of the spring A⁹ by the eccentric or cam A⁵ when the eccentric A⁵ is rotated by 30 the upright shaft A and is moved in practice toward the left by the force of the spring A⁹, which spring A⁹ moves said rod A⁶, and thereby forces the left-hand end of said rod to follow the face of the eccentric or cam A⁵, the 35 cam and spring imparting a vibratory motion to said rod and the sleeve A¹² secured thereto. The distance that the rod A⁶ is vibrated may be governed by manually adjusting the check-nuts A¹⁰ and A¹¹ on the right-hand end of said rod and outside of the frame A², or, in other words, manually moving and securing them in a position nearer the frame or box A² shown in section near to said check-nuts, thereby preventing said coil-spring A⁹ 40 from moving the rod A⁶ any farther than the distance between the frame and said check-nuts, thereby preventing the left-hand end of said rod from following the face of said cam throughout the movement of said cam, and thereby not allowing the cam A⁵ to move 45 said rod A⁶ the full extent of the throw of the cam. The material or leather is moved in practice intermittently or step by step to the skiving-knife and the folding and rubbing 50 device, as and on account of devices herein-after described, operated by power conveyed through said rod A⁶. Therefore it is plain that said material or leather to be skived may be caused to be moved intermittently a greater 55 or less distance by adjusting said check-nuts upon said rod A⁶, as hereinabove described. The construction and assembling of all of the

devices whereupon the feeding is accomplished except said rod A⁶ and said means whereupon said rod is moved in practice, as 70 aforesaid, are described as follows: The feeding device A¹⁶ (shown in Fig. 4, which figure is shown below Fig. 1) is movably supported in practice between the prongs of the device A²⁷, (shown in Fig. 5, which figure is shown at 75 the right of Fig. 4,) the pin A²⁶ (shown in the right-hand upper corner of Fig. 3) being inserted in the holes shown in the prongs of the device A²⁷ and extending through the hole in the center of the feeding device A¹⁶, said pin 80 fitting loosely in the hole in said feeding device A¹⁶ in the manner shown in Fig. 3. The right-hand round part of the device A²⁷ is inserted in the hole in the sleeve A²⁸, as shown in Figs. 1 and 3, said round part fitting loosely 85 in said hole, which sleeve A²⁸ is shown near to the end of the device A²⁷, and the device A³⁰ (shown in Fig. 7 at the right of the device A²⁸) is secured upon the round part of the device A²⁷ by the screw A³¹, (shown in the 90 device A³⁰,) as shown in Figs. 1 and 3, said device A³⁰ having the function of a collar and having a handle thereon, and the trunnions A³² and A³³ of the sleeve A²⁸ are placed in the round holes shown in the bracket A³⁴, 95 which bracket is made fast to the frame A² on the outside of the frame, the part A²⁷ (shown in Fig. 5 below Fig. 1) and the feeding device A¹⁶, movably secured to said part, extending through the frame A² on the inside of the frame A², as shown in the right-hand upper corner of Fig. 3.

It will be observed by the description of the assembling of the parts whereupon the feeding is accomplished that the trunnions A³² and A³³ of the sleeve A²⁸, movably supported in the round holes shown in the bracket A³⁴, (shown in Fig. 8,) form a construction whereupon the feeding device A¹⁶ (shown in Figs. 3 and 1) may be moved up and down. In order to prevent this feeding device A¹⁶ (shown in the right-hand upper corner of Fig. 3) from falling and turning the trunnions A³² and A³³ (shown in Fig. 6 under Fig. 1) in the round holes in the bracket A³⁴, (shown in Fig. 8,) in which they are pivoted, as shown in Fig. 3, and that the feeding device A¹⁶ may be yieldingly supported, the spring A⁴⁴ is devised. The spring A⁴⁴ is secured to the part A⁴⁰, which part A⁴⁰ is pivoted by the screw A⁴¹ to the bracket A³⁹, which screw A⁴¹ fits loosely in a hole in said part A⁴⁰ and is firmly secured into the bracket A³⁹, which bracket is fastened to the outside of the frame A² by the screw A⁴², said bracket extending through the frame A², and said spring A⁴⁴ bears against the device A²⁷, in which the feeding device A¹⁶ is movably secured, and the screw A⁴³ is threaded in the frame A² and forced against the part A⁴⁰, exerting force upon the spring A⁴⁴, thereby causing said spring to hold the feeding device A¹⁶ in the position in which it is shown, and the screw A⁴³ is secured in position by the check-nut thereon. The spring 130

A⁴⁴ is prevented from forcing the feeding device A¹⁶ too high by the screw A⁴⁵, threaded in the right-hand upper corner of the frame A² and extending down vertically and bearing against the device A²⁷, by which device A²⁷ the feeding device A¹⁶ is movably supported. Therefore it is plain that on account of the devices described and the spring A⁴⁴, whereupon the feeding device A¹⁶ is held upward, the feeding device A¹⁶ is yielding supported, or, in other words, it may be pushed downward, causing the spring A⁴⁴ to yield, which spring exerts force, whereupon the feeding device A¹⁶ is normally held in its proper elevation, or in the elevation in which it is shown. It is also plain that the device A²⁷ may be manually turned or adjusted in the hole in the sleeve A²⁸ by the handle of the device A³⁰ (shown in Figs. 7, 3, and 1) and secured by the screw A²⁹ in the sleeve A²⁸, (shown in Figs. 6, 3, 2, and 1,) thereby adjusting the feeding device A¹⁶, movably supported in the device A²⁷, as hereinabove described and as shown in Figs. 5, 3, and 1, out of a vertical position and at any necessary angle to the cutting edge of the rotatory disk skiving-knife A¹⁷, as shown in Figs. 2, 3, and 1.

Attention is called to the flange upon the feeding device A¹⁶, (shown in detail in Fig. 4 under Fig. 1,) which flange extends out from the nearest side of said feeding device. Attention is also called to this flange in Fig. 2 on the left-hand side of said feeding device. Attention is again called to this flange in Fig. 3. The upper end of the lever A¹⁵ is grooved and fits upon the flange of the feeding device A¹⁶, but may be moved or slipped upon said flange. Fast to the upper end of the lever A¹⁵ is a hook, to which one end of the coil-spring A¹⁸ is shown secured, the other end of the coil-spring A¹⁸ being shown secured to a screw shown in the support A¹⁹, shown secured to the bracket A', which spring is shown expanded or stretched beyond its normal length, exerting force upon the lever A¹⁵. The lower end of the lever A¹⁵ is shown forked and fitted upon the roll A¹⁴, which roll is shown movably secured upon the stud A¹³ (shown also in detail in Fig. 10 under Fig. 3) and is prevented from coming off of said stud by the hexagon nut shown on said screw in Fig. 3. When the rod A⁶ (shown at the bottom of Fig. 3 and in detail in Fig. 10) is moved toward the right in practice by the cam A⁵, as hereinabove described, thereby carrying the roll A¹⁴, the lever A¹⁵, shown connected with said roll, is moved toward the right by said roll and the flange of the feeding device A¹⁶ is gripped by said lever and the lower part of said feeding device is carried toward the right and the upper part of said feeding device is thereby carried toward the left in order to move the leather toward the left or toward the rotatory disk skiving-knife A¹⁷ and the folding and rubbing device A⁴, and the coil-spring A¹⁸, shown

secured to the hook shown in the lever A¹⁵ and to the screw shown in the bracket A¹⁹, is expanded or stretched beyond its normal length, 70 and the spring A⁹ (shown in Fig. 3 secured to the screw shown in the sleeve A¹² shown on the rod A⁶ and shown secured to the screw shown in the bracket A') is also expanded, which spring A⁹ moves the rod A⁶ toward the 75 left in practice, the cam A⁵ permitting, thereby moving the lower end of the lever A¹⁵ toward the left, allowing the spring A¹⁸, shown secured to the hook in the lever A¹⁵, to move or slip the lever A¹⁵ toward the left upon the 80 flange of the feeding device A¹⁶, while the feeding device A¹⁶ is prevented from being moved by this movement by the cylindrical chock or "trig" A⁴⁶, forced down in the V-shaped opening (shown in Fig. 3 by dotted 85 lines) between the face of the feeding device A¹⁶ and the back of the slot in the device A²⁷ (shown also by dotted lines) by the spring A⁴⁷, shown secured to the device A²⁷ by the screw A⁴⁸. 90

In Fig. 2 the bottom part of the presser-foot B is shown above the feeding device A¹⁶ and near thereto. The screw having the hexagon head shown in front of the presser-foot B is inserted in a slot shown by dotted lines 95 in the presser-foot under the hexagon head and is threaded in another piece in the manner shown in Fig. 3, clamping the presser-foot B to the other piece by said screw, as is shown in Fig. 3, and leaving the presser-foot 100 adjustable to the right and left on the piece to which it is secured, as is plain by this construction in Fig. 2. The piece to which the presser-foot B is thus secured thereby becomes a part of the presser-foot B. This part 105 to which the presser-foot B is thus secured is movably secured to the arm B²² (shown in Figs. 2 and 3) by the two screws shown in Fig. 2 immediately above the hexagon screw, which screws extend through the slot in the 110 upper part of the presser-foot B (shown by dotted lines under the round heads of said screws) and are threaded in the arm B²², which is rigidly secured to the frame A², affording an adjustment of the presser-foot up 115 and down. Therefore it is plain by the description thereof that this presser-foot is rigidly secured, but is manually adjustable toward the right and left and is also adjustable up and 120 down.

The presser-bar B²¹ is shown in Figs. 1, 2, and 3 movably secured in the arm B²². Upon the presser-bar B²¹, between the bearings in which it is movably secured, a collar is shown 125 rigidly secured to said presser-bar B²¹. Resting upon this collar the end of the long flat spring B²³ is shown, which spring presses the presser-bar B²¹ downward with great force as far as the knurled nut on the top of the 130 presser-bar B²¹ permits. Said flat spring B²³ is secured to the arm B²² by the first screw (shown by dotted lines in Fig. 2) at the left from the screw B¹⁰ in the arm B²², and said

flat spring is forced down upon the collar of the presser-bar B^{21} , thereby forcing the presser-bar downward by the second screw at the left from the screw B^{10} in the arm B^{22} , (shown also by dotted lines in Fig. 2,) which screw is shown knurled in Fig. 3 and extends through a slot in the spring B^{23} and is threaded into the frame A^2 , by which screw the amount of pressure upon the presser-bar B^{21} 5 may be manually governed. Upon the bottom of the presser-bar B^{21} the presser B^{20} is shown in Figs. 2 and 3 rigidly secured, which presser B^{20} is normally held and yieldingly supported at such an elevation above 10 the device A^4 on account of the above-described devices that the skived part of the leather before it is folded may be moved under the presser B^{20} without binding the leather; but the folded part of the leather being thicker 15 than the skived part of the leather is forced against said presser B^{20} in practice and rubbed by the highest portion of the operative part 20 of the device A^4 at proper times. When the feeding device A^{16} is moved in practice intermittently or little by little, as hereinabove described, the part of leather near the edge of the leather is thereby moved intermittently 25 between the presser-foot B and the feeding device A^{16} and is moved intermittently against 30 the cutting edge of the rotatory disk skiving-knife A^{17} at an angle to said cutting edge of said rotatory disk skiving-knife by said feeding device, and said leather is skived by said skiving-knife little by little near the edge of 35 said leather and shaped like a wedge on account of the intermittent movement imparted to the leather by said feeding device and is intermittently moved up on the device A^4 for folding and rubbing the skived part of the 40 leather, the body of the leather being toward the left, and the skived part is slit and folded, as and by devices hereinafter described, as it is thus passing, and the shaving cut from said leather as it is thus passing falls upon a 45 sheet-iron chute of common construction, which chute is secured to the frame A^2 and is adapted to prevent the shavings from getting into the operative mechanism of the machine. The position of one side of this chute 50 is indicated at the left-hand side of Fig. 1 by a dotted line outside of the frame A^2 , near to said frame and extending parallel with said frame, said dotted line passing through the heating device D^{14} , and the other two sides of 55 said chute are indicated by two dotted lines very near together. This chute is also shown in other figures; but no reference character is placed thereon, because reference to the chute is not considered necessary, as nothing 60 new is claimed in the construction thereof, and because the chute is not a part of the operative mechanism whereupon the unitary result of the invention is accomplished, the use of said chute being wholly to prevent the 65 shavings from falling into the operative mechanism of the machine.

Having shown and described the mechan-

ism comprising the rotatory disk skiving-knife A^{17} and the feeding device A^{16} yieldingly supported and the means whereupon the feeding device A^{16} is automatically moved intermittently little by little in order to move the leather little by little intermittently against the cutting edge of said rotatory disk skiving-knife A^{17} and having also described the 70 general shape and construction of the device A^4 for folding the skived part of the leather and for rubbing the folded part of the leather from the folded edge inward and set forth the operation of the feeding device A^{16} and the 75 rotatory disk skiving-knife A^{17} and set forth the result accomplished on account of said skiving-knife and feeding device, it should be understood that I do not broadly claim all kinds of devices whereupon the leather may 80 be moved intermittently or otherwise, but only those which are comparatively the same as the feeding device shown and described. 85 Attention is called to the specific construction and novel features of the device whereupon the skived part of the leather is folded and rubbed from the folded edge of the leather inward. In Fig. 3 this device A^4 is shown in side elevation. In Fig. 1 the device A^4 is shown in plan and is inclosed by the largest 90 circular line in the view. The next to the largest circular line indicates the top of the bevel shown in side elevation in Fig. 3. Attention is particularly called to this bevel, the device itself being made thick for strength 95 and beveled like a wedge. It should be fully understood that, as it is hereinabove described, this device A^4 is rotatable and that the direction of its movement is from the skived edge of the leather inward at about 100 right angles to said skived edge, and it should be fully realized that this device A^4 , made thick for strength and beveled for utility and recessed as and for the purpose hereinafter described and adapted to be rotated and 105 moved from the skived edge inward, is regarded as the chief device of this invention. In actual construction the operative part of the device A^4 (shown in Figs. 1, 2, 3, and 15) or, in other words, that part of the device A^4 110 which contributes in the production of the folded edge by acting upon the leather is designed to be irregular, or, in other words, some portions of the operative part of the device A^4 are designed to be higher than other portions of said operative part. The operative 115 part of the device A^4 is shown recessed clear through the device A^4 from the inclined portion B^{19} of the operative part of the device A^4 to the inclined portion of the operative part of the device A^4 , (indicated by the first reference character Z at the left of the reference character B^{19} ,) because the recess shown as 120 extending clear through the device A^4 shows the operativeness of the invention better than it would if it were shown as not extending clear through the device A^4 , and besides this recess another portion of said operative 125 part of the device A^4 is shown recessed from

the inclined portion indicated by the reference character Z to the inclined portion thereof indicated by the second reference character Z near thereto, which recess Z Z is not shown as extending clear through the device A⁴. Therefore it is shown by Figs. 1, 2, 3, and 15 that said operative part of the device A⁴ is recessed at various places to various depths, and also that said operative part of the device A⁴ comprises a surface some parts of which are higher than other parts. This device is not only a folding and rubbing device, but it is also a cementing device, or, in other words, a device for depositing cement upon the skived surface of the leather before it is folded, as will hereinafter appear. Upon the horizontal part of the recessed portion Z Z of the operative part of the device A⁴ cement is mechanically deposited in practice as and by devices hereinafter described and is deposited upon the skived surface of the leather before it is folded in practice by said recessed portion Z Z as and by devices hereinafter described. The reason why that the portion Z Z of the operative part of the device A⁴ is made lower than other portions of said operative part is that if it were not so the cement would be distributed over the surface of the highest portion of the operative part of the folding and rubbing device A⁴, or, in other words, upon that part which rubs the folded part of the leather after it is folded, and this is undesirable; but on account of the portion Z Z of the operative part of the device A⁴, upon which cement is deposited in practice as and by devices hereinafter described, being made lower than other portions of the operative part of the folding and rubbing device A⁴ cement is deposited in practice upon the skived surface of the leather by said recessed portion Z Z of the operative part of the device A⁴ before the skived part of the leather is folded, thereby enabling the highest portion of said operative part of said folding and rubbing device A⁴ to rub in practice the opposite side of the leather from the side on which cement is deposited, thereby preventing cement from being distributed upon said highest portion. Therefore the operative part of the device A⁴, comprising recessed portions and a surface some parts of which are higher than other parts, is a distinct novel feature of this invention.

Having shown and described that the device A⁴ for folding and rubbing the skived part of the leather is also a cementing device for depositing cement upon the skived part of the leather before it is folded and stated that cement is deposited in practice upon a recessed portion of the operative part of the device A⁴ for folding and rubbing the skived part of the leather as and by devices hereinafter described and that cement is rubbed in practice by said cementing device upon the skived part of the leather, attention is called to the description of the receptacle in which

cement is kept and the devices whereupon cement is automatically taken in practice from said cement-receptacle and deposited upon said recessed portion of said operative part of said device A⁴. The cement-receptacle C (shown in detail in Fig. 13) is in practice manually filled with cement. Two projections or legs are shown upon the front side of said receptacle C, standing out from each upper corner of said receptacle, and a round hole is shown through each projection or leg. Said cement-receptacle C is secured to the frame A², as shown in Figs. 1 and 3, by screws (shown by dotted lines) extending through said holes in said projections or legs and threaded into the frame A², and said receptacle is also shown secured to the bracket A' by two flat-head screws, (shown at the extreme left in Fig. 3,) extending through the bracket A' and threaded into the bottom of said receptacle. The shaft C' is shown journaled in said cement-receptacle and extends through said cement. Fast upon said shaft is the cement-wheel C², shown projecting above the top of the cover of said receptacle. Movably secured to said shaft C' is shown the pawl-carrier C³. A spring C⁴ is shown fast to said receptacle and bears against said pawl-carrier C³ and normally forces said pawl-carrier C³ against the screw C⁵, shown fast in said receptacle. Fast in said pawl-carrier C³ is shown a piece of rawhide C⁶. The pawl C⁷ is loose upon the screw C⁸, which screw is shown fast in said pawl-carrier. The end of the pawl C⁷ is shown held in contact with the ratchet C⁹ by the spring C¹⁰, shown fast to the screw C¹¹, shown in said pawl, and the screw C¹², shown in said pawl-carrier, and said ratchet is shown secured to the shaft C'. A device or striker C¹³ is shown in Figs. 9 and 1 secured to and adapted to be carried by said device A⁴. It is plain by Fig. 9, in which a section of said device A⁴ is shown, that the device or striker C¹³ is carried by the device A⁴ into contact with the rawhide C⁶, (shown in Fig. 13,) fast in said pawl-carrier C³, every time said device A⁴ is rotated. It will be observed that said pawl-carrier is thereby moved a short distance in one direction by said device or striker every time the rawhide C⁶, fast in said pawl-carrier, is struck thereby, thereby forcing the pawl C⁷, carried by said pawl-carrier C³, to engage and turn the ratchet C⁹, the shaft C', secured thereto, and the cement-wheel C², fast to said shaft, intermittently or little by little, thereby taking cement out of said receptacle on the face of said cement-wheel C² at every revolution of the device A⁴, the spring C⁴ moving the pawl-carrier C³ in the opposite direction from the direction in which it is moved by the striker C¹³ every time it is moved by the device or striker C¹³. After cement is in practice thus automatically taken out of said receptacle upon the face of said cement-wheel C² the cement is mechanically taken from said cement-wheel and is

mechanically deposited upon the recessed portion Z Z of the operative part of said device A⁴ for rubbing cement upon the skived surface of the leather, which portion Z Z is in practice passing by said cement-wheel at about the same time that cement is taken out of said receptacle on account of devices described as follows: The device A⁴ is shown in Figs. 1, 2, 3, 14, and 15. The cam C¹⁷ is shown upon the top of said device A⁴, secured to said device A⁴. Said cam C¹⁷ is covered with a cover C¹⁸. (Shown in Figs. 2, 3, 14, 15, and 16.) Said cover C¹⁸ is shown secured to the bracket C¹⁹ by the screws C²⁰ and C²¹. (Shown in the upper part of Figs. 1 and 14 and also near the left-hand upper corner of Fig. 3.) Said cover C¹⁸ is also shown secured to the brackets C²² and C²³ by the screws C²⁴, C²⁵, C²⁶, and C²⁷, as shown in Figs. 1, 14, and 16. These brackets are secured to the cement-receptacle C, as is plain by Figs. 1, 14, and 16. There is a part C²⁸, (shown in Fig. 2,) fast to said cover C¹⁸, that extends toward the right. Said part is shown fast upon the frame A². Thus it is plain that said cover C¹⁸ is supported at four different places. Every time that said device A⁴ is rotated said cam C¹⁷, (shown in Figs. 1, 2, 3, 14, and 15,) fast to said device A⁴, is rotated. The cement-brush bar C²⁹, shown mounted in the ways C³⁰ and C³¹, (shown in Figs. 1, 3, 14, 15, and 16,) is shown held against the cam C¹⁷ by the coil-spring C³², shown fast to a pin C³³, shown in said cement-brush bar, and to a pin C³⁴, shown fast in said cover C¹⁸. Therefore it is plain that said cement-brush bar C²⁹ is moved in practice, in one direction by said cam C¹⁷ and in the opposite direction by said coil-spring C³². In Figs. 1, 3, 14, and 15 the cement-brush C³⁵ is shown bearing upon the cement-wheel C² in the position it is in practice taking cement from said cement-wheel. It is plain by the shape of said cam C¹⁷, (shown in Fig. 1,) that said cement-brush is moved in practice from the position shown in said figures to the recessed portion Z Z of the operative part of said device A⁴, hereinabove described, which recessed portion Z Z is shown in Figs. 1 and 15, and that cement is taken in practice from said cement-wheel C² by said cement-brush C³⁵ and deposited upon said recessed portion Z Z of said operative part of said device A⁴. The construction of the cement-brush C³⁵ is shown in Fig. 17. Said brush is made of bristles by pulling them double into the hole in said brush-bar by the wire C³⁶, and the end of the wire C³⁶ is secured by the screw C³⁷, thereby securing the bristles in said brush-bar; but the device for taking cement off from said cement-wheel C² is not restricted to this form, but may be any device suitable for the purpose for which this brush is used. I believe that such devices have not been heretofore devised, whereupon cement taken out from a cement-receptacle is then taken and deposited upon the skived surface of a piece of leather, and I also believe that such means

have not been combined with operative parts of skiving-machines or skiving and folding machines and have not heretofore contributed in the production of a folded edge, and therefore I believe that the devices employed in this machine, whereupon cement is taken from said cement-wheel and deposited upon the skived surface of the leather, form a novel combination of devices comprised in this invention, which combination contributes to the production of the unitary result of the machine—viz., a folded edge.

The thumb-screw C³⁸ (shown at the left-hand lower corner of Fig. 3 and shown also in Fig. 1) extends through a hole in the frame A², fitting loosely in said hole, the head of said screw bearing against the outer side of said frame and a collar fast to said screw bearing against the inner side of said frame, said screw being also threaded into the bottom of the adjustable knife-shaft support A²², (shown in Figs. 1 and 2,) which adjustable knife-shaft support comprises the two journal-bearings 90 in which the skiving-knife shaft A²⁰ is rotatably secured. Said adjustable knife-shaft support is held firmly upon the bottom of the frame A² by the hand-screw C³⁹, (shown in Figs. 1 and 2,) which hand-screw is shown threaded upon a screw, (shown in Figs. 1 and 2,) which screw extends through a hole in the bottom of the frame A² and through a slot (shown in Fig. 1) in said adjustable knife-shaft support, and when said rotatory disk skiving-knife A¹⁷ is worn so small that the cutting edge thereof is not in the proper relative position with the edge of the operative part of the device A⁴ the adjustable knife-shaft support A²² may be loosened on the frame A² by said hand-screw, and the knife-shaft support, with the knife-shaft A²⁰ mounted therein, and the rotatory disk skiving-knife A¹⁷, secured to said shaft, may be manually forced forward in practice by said thumb-screw C³⁸ until the cutting edge of said skiving-knife A¹⁷ is in the proper position, and then said knife-shaft support A²² may be again firmly fixed or secured to the frame A² by said hand-screw. It should be understood that the means whereupon said skiving-knife may be thus moved into position after it is worn so small that it is out of proper relative position with the edge of said operative part of said device A⁴ for folding and rubbing is also a novel feature of this invention.

There are operative devices in this machine—viz., devices whereupon the slitting of the skived part of the leather at about right-angles to the skived edge of the leather is accomplished—which contribute to the unitary result attained by the machine—viz., a folded edge—which devices have not been heretofore described; but as the nature of the entire combination of devices or this machine is such that a description of the operative devices referred to would not be fully comprehensive except they be described in combination with other operative parts after due

deliberation it has been deemed best that they be described in the operation of the machine, which is as follows: The leather is moved about one-eighth of an inch in the manner hereinabove described by the feeding device A¹⁶, operated by devices hereinabove described, against the skiving-knife A¹⁷, and is thereby skived a short distance or about one-eighth of an inch, and the device A⁴ is so timed with the devices whereupon the feeding device is moved that the leather is moved in upon said recessed portion Z Z, (shown in Figs. 1, 2, and 15,) and the cam-surface A²⁵ on the wheel A⁸ (shown in Fig. 3) is forced into contact with the roll A²³, (shown in Figs. 1 and 2,) which roll is movably secured to the screw A²⁴, which screw is fast in the lever B', (shown in Figs. 1 and 2,) thereby moving the lever B' fast to one end of the shaft B², (shown in Fig. 1,) thereby turning the shaft B² in the bracket B³, (shown in Fig. 1,) which bracket is secured to the frame A², thereby moving the lever B⁴, (shown in Fig. 2,) fast to the other end of the shaft B², and also shown in Fig. 1, the reference character thereon being near the pivotal point of the lever B⁸ in Fig. 1 in such a manner as to move the link B⁵, (shown in Fig. 2,) pivoted to the lever B⁴ by the screw B⁶, upward against the power of the spring B⁷, secured to a screw in the arm B²² and to a screw in the link B⁵, and moving the right-hand end of the lever B⁸, pivoted to the link B⁵ by the screw B⁹, upward upon the pivot B¹⁰, fast in the arm B²², thereby moving the left-hand end of the lever B⁸ downward and carrying the link B¹¹, pivoted to the lever B⁸ by the screw B¹², and the bracket B¹³, pivoted to the link B¹¹ by the screw B¹⁴, and the knife-bar B¹⁵, movably secured to the arm B²², and rigidly secured to the bracket B¹³, downward, thereby carrying the bending device or spring B¹⁸, shaped somewhat like the letter J and secured to the lower part of the knife-bar B¹⁵, the lower end of which bending device is shown in Fig. 2 by dotted lines behind the knife B¹⁶, downward, the thickness and width of the lower end of which bending device are shown by dotted lines in Fig. 3, thereby pressing the skived part of the leather down upon the recessed portion Z Z of the operative part of the device A⁴, which bending device B¹⁸ is thereby forced to yield or bend, and the knife B¹⁶, (shown in Figs. 2 and 3,) the lower end of which knife is beveled like a chisel and sharp, which knife is fast to the lower end of the knife-bar B¹⁵, is forced by said knife-bar down upon the skived part of the leather, one side and cutting edge of said knife shearing past and rubbing the shearing device or block B¹⁷, rigidly secured to the frame A² and shown in Fig. 2, and the other side of said knife almost rubbing against the periphery of the moving device A⁴, thereby cutting a slit about one-eighth of an inch long through the leather and at about right angles to the skived edge, thereby disconnecting the skived part from the part not skived, and the cement

deposited upon said recessed portion Z Z of the operative part of the device A⁴, as and by devices hereinabove described, is rubbed upon the skived surface of the leather, and the recess or opening in the inoperative part of the device A⁴, which device is being moved in the direction indicated by the arrow shown thereon, is mechanically carried under the part of the leather upon which the bending device B¹⁸ is pressing, whereupon the skived and slit part of the leather is bent downward by the spring B¹⁸ into said recess or opening and is instantly caught and folded under by the inclined portion B¹⁹, and is rubbed in the direction of the folded edge inward by the highest portion of the operative part of the device A⁴, which device is hot, being heated by the gas device D¹⁴, as hereinafter described, said skived part of the leather being firmly but yieldingly held down upon the highest portion of the operative part of the device A⁴, while the folded part is rubbed by the presser B²⁰, fast to the presser-bar B²¹, (shown in Figs. 2 and 3,) which presser-bar is movably supported in the arm B²² and firmly but yieldingly held down by the spring B²³, (shown in Figs. 1, 2, and 3,) secured to the arm B²² by a slotted screw (shown by dotted lines in Fig. 2) at the left of the pivot-screw B¹⁰ in the arm B²², said spring B²³ being held downward upon a collar shown secured to the presser-bar B²¹ in Figs. 2 and 3 by a thumb-screw, (shown by dotted lines in Fig. 2 at the left of said slotted screw,) said thumb-screw extending through a slot in said spring and threaded into the arm B²².

Repetitions of the above-described operation produce a folded edge of a piece of leather that may be thicker, but substantially the same thickness as the leather before it is folded.

I do not broadly claim all kinds of devices whereupon slitting may be accomplished, but only those which are comparatively the same as the devices whereupon the slitting is accomplished shown and described.

Let it be understood that the invention of the device A⁴, adapted to apply cement and to fold and rub, as hereinabove described, the rotatory disk skiving-knife A¹⁷, the slitting or shearing device B¹⁶, the feeding device A¹⁶, the bending device B¹⁸, the presser B²⁰, and the presser-foot B, each and all made substantially as shown and described, and the combining of these devices substantially as shown and described, so that they may all coöperate together upon the leather in proximity to each other, as described, so that a folded edge can be made upon parts of shoes which have short curves, is the result of very severe and protracted taxation of my creative faculties and, as this is the first machine whereupon parts of shoes could be skived and folded around short curves, is very important.

In order that all the cement that is placed upon the recessed portion Z Z of the opera-

tive part of the device A⁴ may be used upon the leather every time said cement is put in practice upon the recessed portion Z Z, as described, the device C¹⁴ is devised. The device C¹⁴, shown movably secured to the cover of said receptacle C by the screw C¹⁵, extending through the slot shown in said device C¹⁴ and threaded into the cover of said receptacle, which device C¹⁴ is also movably connected with the thumb-screw C¹⁶, which extends through and fits loosely in a hole in the device C¹⁴, the body of the thumb-screw bearing against one side of the device C¹⁴, as shown in Fig. 13, and a collar (shown in Fig. 15) fast to said thumb-screw bearing against the other side of the device C¹⁴ may be moved toward or from the cement-wheel C² by the thumb-screw C¹⁶, thereby placing the chisel-shaped end of the device C¹⁴ at a proper distance from the cement-wheel C² to allow the cement-wheel C² to take a specific amount of cement out of the receptacle C, or, in other words, to allow said cement-wheel C² to take cement out of said receptacle just as fast as it is needed upon the leather, whereupon the accumulation of cement upon the recessed portion Z Z of the operative part of the device A⁴ is prevented. It will be observed that this cement-receptacle is so made that it is nearly air-tight in order that the liquid in the cement therein may not evaporate.

It is plain that before the unitary result of this machine—viz., a folded edge can be produced—said skiving-knife A¹⁷ must be ground or sharpened. Therefore, the mechanism whereupon said skiving-knife may be mechanically ground or sharpened is a component part of the machine which is the subject of the present application and is shown in the drawings and is described as follows: In Figs. 2 and 1, the upright shaft D is shown journaled in the bearings D' and D², which bearings are shown fast to the frame A². Shown fast to said shaft D is the emery-wheel shaft support D⁴, having a handle, near which the reference character D⁴ is placed, said emery-wheel-shaft support D⁴ also having two arms, the upper one of which is designated in Figs. 1 and 2 by the reference character D³, and each one of these arms supports a journal-bearing. (Shown in Fig. 2.) The emery-wheel shaft D⁵ is shown journaled in said journal-bearings of said emery-wheel-shaft support. In said shaft is shown the groove D⁶. Upon said shaft is shown the friction-wheel D⁷. The screw D⁸ is shown screwed tightly into said friction-wheel, and the point of said screw fits loosely in said groove D⁶ in said emery-wheel shaft D⁵. Therefore it is plain that the friction-wheel D⁷ is rotated in practice with said shaft, but is movable vertically upon said shaft. Above said friction-wheel D⁷ and bearing against said friction-wheel and around said shaft D⁵ is shown the coil-spring D⁹, the end of which enters into the collar shown upon the shaft D⁵ above said spring, which collar is shown secured to the shaft D⁵ by a

screw, and on the top of said emery-wheel shaft D⁵ the emery-wheel D¹¹ is secured, as shown in Fig. 2. In Fig. 11 said friction-wheel D⁷ is shown in detail, and a ring, of raw-hide, D¹⁰ is shown secured upon the inclined part of said friction-wheel. The grinding of said skiving-knife A¹⁷ may be accomplished by the emery-wheel D¹¹, (shown fast to said shaft D⁵), as follows: The handle of said emery-wheel-shaft support D⁴ (shown in Figs. 1 and 2) may be moved in practice by hand, thereby moving the shaft D, (shown in Figs. 2 and 1,) secured to said emery-wheel-shaft support D⁴ and mounted in the journal-bearings D' and D², the emery-wheel shaft D⁵, shown rotatably secured in the journal-bearings of said emery-wheel-shaft support, and all the devices shown secured to said emery-wheel shaft, thereby forcing the inclined rawhide surface D¹⁰ (shown in Fig. 11) of the friction-wheel D⁷ (shown also in Figs. 2 and 1) into contact with the inclined surface of the friction-wheel D¹², (shown in Fig. 3 and shown also in Fig. 2,) secured by a screw to the skiving-knife shaft A²⁰, which friction-wheel is rapidly rotated by the skiving-knife shaft A²⁰, to which said skiving-knife A¹⁷ is secured, and thereby forcing the emery-wheel D¹¹, secured upon the top end of said emery-wheel shaft D⁵, against the skiving-knife A¹⁷ near its cutting edge, and thereby forcing the friction-wheel D⁷ upward upon the emery-wheel shaft D⁵ against the force of the coil-spring D⁹, whereupon the friction-wheel D⁷, the emery-wheel shaft D⁵, and the emery-wheel D¹¹ are rotated, thereby grinding said skiving-knife. After said skiving-knife is ground sharp the handle D⁴ should be released, thereby allowing the coil-spring D¹³, (shown by dotted lines near the right-hand lower corner of Fig. 1,) secured to the emery-wheel-shaft support D⁴ and to the inside of the frame A², a part of which spring is also shown in Fig. 2, to pull the emery-wheel-shaft support D⁴, the emery-wheel shaft D⁵, and all the devices secured to said emery-wheel shaft back in the opposite direction from that in which they are moved by hand and to thereby cause the grinding to immediately cease.

The device A⁴ (shown in Figs. 1, 2, and 3) is heated in practice by the gas device D¹⁴. (Shown in Figs. 1, 2, and 12.) The construction of this gas device is shown in detail in Fig. 12. The tube D¹⁵ is shown broken. If gas were applied directly from a gas jet or tip against the device A⁴ and if it were lighted while thus applied, in a few minutes said device would be covered with lampblack from the smoke caused by the burning gas. To prevent the accumulation of lampblack, the gas device shown in Fig. 2 is employed. The draft of the lighted gas inside of the gas device draws air in at the holes D¹⁶ and D¹⁷ in the bottom of said device in practice, and a blue flame is thereby forced out of the top of said gas device through the hole D¹⁸. This flame is practically free from smoke by which

lampblack is accumulated, and therefore little or no lampblack is formed in practice. This gas-burner is not of my invention, but is practically the same as the heating device known as the "Bunsen burner." It is evident that other means for heating said device A⁴ may be employed besides this gas device, and it is also evident that other combustibles may be used besides gas.

10. Having hereinabove described the accompanying drawings of a machine in which this invention is embodied and having carefully set forth the novel features and combinations of this invention, I claim as follows:

15. 1. In a skiving and folding machine the following combination of instrumentalities, viz: a folding device; means for operating the same; a skiving device comprising a skiving-knife; a feeding device the corrugated part 20 of which is at an angle to the cutting edge of the skiving-knife; a presser-foot near to said feeding device; manually-adjustable means, whereupon, said angle may be changed, whereupon the leather may be skived at different 25 angles; means, whereupon, the feeding device is operated; and means whereupon, the skiving device is operated independent of any other part of the machine.

2. In a skiving and folding machine the following combination of instrumentalities, viz: a folding device; means for operating the same; a skiving device comprising a skiving-knife; a feeding device the corrugated part 30 of which is at an angle to the cutting edge of the skiving-knife; a rigid presser-foot secured near to said feeding device; manually-adjustable means, by which said angle may be changed; means, whereupon, the feeding device is yieldingly supported; means, whereupon, the feeding device may be actuated; and means, whereupon, the skiving device may be actuated independent of any other part of the machine.

3. In a skiving and folding machine the following combination of instrumentalities, viz: a folding device; means for operating the same; a skiving device comprising a skiving-knife; a feeding device the corrugated part 45 of which is at an angle to the cutting edge of said skiving-knife; a presser-foot near to said feeding device; manually-adjustable means, whereupon, said angle may be changed, whereupon, the leather may be skived at different angles; means, whereupon, the feeding device is operated; a slitting device, whereupon, slits are cut in the material at right angles to the edge of the material; means, whereupon, the slitting device is operated; and means, whereupon, the skiving device is operated independent of any other part of the machine.

4. In a skiving and folding machine the following combination of instrumentalities, viz: a folding device; means for operating same; a skiving device comprising a skiving-knife; a feeding device the corrugated part of which 60 is at an angle to the cutting edge of the skiving-knife; a rigid presser-foot secured near

to said feeding device; manually-adjustable means, by which said angle may be changed; means, whereupon, the feeding device is yieldingly supported; means, whereupon, the feeding device may be actuated; a slitting device, whereupon, slits are cut in the material at right angles to the edge of the material; means, whereupon, the slitting device is operated; and means, whereupon the skiving device may be actuated independent of any other part of the machine.

5. In a skiving and folding machine the following combination of instrumentalities, viz: a skiving device; a feeding device; a slitting device; a bending device; a cementing device; a folding and rubbing device; and a pressing device; and suitable means, whereupon, they may be actuated and the skiving device actuated independent of any other part of the machine.

6. In a skiving and folding machine the following combination of instrumentalities, viz: a folding mechanism; a skiving device; a feeding device; and a cementing device; and means, whereupon, they may be actuated and the skiving device actuated independent of any other part of the machine.

7. In a skiving and folding machine the following combination of instrumentalities, viz: a skiving device; a feeding device; a bending device; a folding device; and a pressing device; and means, whereupon, they may be actuated and the skiving device actuated independent of any other part of the machine.

8. In a skiving and folding machine the following combination of instrumentalities, viz: a skiving device; a feeding device; and a slitting device; and means, whereupon, they may be actuated and the skiving device actuated independent of any other part of the machine.

9. In a skiving and folding machine the following combination of instrumentalities, viz: a skiving device; a feeding device; a slitting device; a bending device; a folding device; and a pressing device, and means, whereupon, they may be actuated and the skiving device actuated independent of any other part of the machine.

10. The following combination of instrumentalities, viz: a feeding device adapted to move a piece of leather; a mechanism whereupon said feeding device may be actuated; a presser-foot or device secured near to said feeding device; a skiving-knife; a mechanism whereupon said skiving-knife may be actuated; a slitting device adapted to cut a slit at about right angles to the edge of the skived part of a piece of leather and extending inward about one-eighth of an inch; a mechanism whereupon said slitting device may be vibrated; a device against which the cutting edge of said slitting device is vibrated in cutting said slit.

11. The following combination of instrumentalities, viz: a feeding device adapted to move a piece of leather; a mechanism whereupon said feeding device may be actuated; a

presser-foot or device secured near to said feeding device; a slitting device adapted to cut a slit at about right angles to the edge of the part of the leather to be folded and extending inward about one-eighth of an inch; a mechanism whereupon said slitting device may be vibrated; a device against which the cutting edge of said slitting device is vibrated in cutting said slit; a thick, recessed, beveled, disk-shaped device adapted to fold, press and rub leather; a bending device adapted to bend the part of the leather to be folded and press it down upon a recessed portion of the operative part of said folding, pressing and rubbing device; a mechanism whereupon said bending device may be vibrated; means whereupon said folding, pressing and rubbing device may be rotated and the operative part of said device thereby carried in a direction inward from the edge of the part of the leather to be folded, at about right angles to said edge, thereby folding, pressing and rubbing said leather; a presser against which said leather is held while it is pressed and rubbed by said folding, pressing and rubbing device.

12. The following combination of instrumentalities, viz: a cement-receptacle; a wheel or cement-carrying device movably supported in said cement-receptacle and extending out through said cement-receptacle; means whereupon said wheel or cement-carrying device may be mechanically moved whereupon a specific amount of cement is carried out of said cement-receptacle by said wheel or cement-carrying device; a brush or device adapted to take cement from the wheel or cement-carrying device and deposit the cement upon a recessed surface of a device for depositing cement upon a piece of leather and also for folding, pressing and rubbing said leather; means whereupon said brush or device may be mechanically operated.

13. The following combination of instrumentalities, viz: a cement-receptacle; a wheel or cement-carrying device movably supported in said cement-receptacle and extending out through said cement-receptacle; means whereupon said wheel or cement-carrying device may be mechanically moved whereupon a specific amount of cement is carried out of said cement-receptacle by said wheel or cement-carrying device; a manually-adjustable device adapted to be moved and secured at various distances from said wheel or cement-carrying device whereupon the specific amount of cement taken from said cement-receptacle by said wheel or cement-carrying device may be varied accurately; a brush or device adapted to take cement from the wheel or cement-carrying device and deposit the cement upon a recessed surface of a device for depositing cement upon a piece of leather and also for folding, pressing and rubbing said leather; means whereupon said brush or device may be mechanically operated.

14. The following combination of instru-

mentalities, viz: a feeding device adapted to move a piece of leather; a mechanism whereupon said feeding device may be actuated; a presser-foot or device secured near to said feeding device; a slitting device adapted to cut a slit at about right angles to the edge of the part of the leather to be folded and extending inward about one-eighth of an inch; a mechanism whereupon said slitting device may be vibrated; a device against which the cutting edge of said slitting device is vibrated in cutting said slit; a thick, recessed, beveled, disk-shaped device adapted to fold, press and rub leather; a cement-receptacle; a wheel or cement-carrying device movably supported in said cement-receptacle and extending out through said cement-receptacle; means whereupon said wheel or cement-carrying device may be mechanically moved whereupon a specific amount of cement is carried out of said cement-receptacle by said wheel or cement-carrying device; a brush or device adapted to take cement from the wheel or cement-carrying device and deposit the cement upon a recessed surface of a device for depositing cement upon a piece of leather and also for folding, pressing and rubbing said leather; means whereupon said brush or device may be mechanically operated; a bending device adapted to bend the part of the leather to be folded and press it down upon a recessed portion of the operative part of said folding, pressing and rubbing device; a mechanism whereupon said bending device may be vibrated; means whereupon said folding, pressing and rubbing device may be rotated and the operative part of said device thereby carried in the direction inward from the edge of the part of the leather to be folded, at about right angles to said edge, thereby rubbing cement upon said part of the leather to be folded and folding, pressing and rubbing said leather; a presser against which said leather is held while it is pressed and rubbed by said folding, pressing and rubbing device.

15. The following combination of instrumentalities, viz: a feeding device adapted to move a piece of leather; a mechanism whereupon said feeding device may be actuated; a presser-foot or device secured near to said feeding device; a skiving-knife; a mechanism whereupon said rotatory disk skiving-knife may be actuated; a slitting device adapted to cut a slit at about right angles to the edge of the skived part of the leather and extending inward about one-eighth of an inch; a mechanism whereupon said slitting device may be vibrated; a device against which the cutting edge of said slitting device is vibrated in cutting said slit; a thick, recessed, beveled, disk-shaped device adapted to fold, press and rub leather; a bending device adapted to bend the skived part of the leather and press it down upon a recessed portion of the operative part of said folding, pressing and rubbing device; a mechanism

whereupon said bending device may be vibrated; means whereupon said folding, pressing and rubbing device may be rotated and the operative part of said device thereby carried in a direction inward from the edge of the skived part of the leather, at about right angles to said edge, thereby folding, pressing and rubbing said leather; a presser against which said leather is held while it is pressed and rubbed by said folding, pressing and rubbing device.

16. The following combination of instrumentalities, viz: a feeding device adapted to move a piece of leather; a mechanism whereupon said feeding device may be actuated; a presser-foot or device secured near to said feeding device; a skiving-knife; a mechanism whereupon said rotatory disk skiving-knife may be actuated; a slitting device adapted to cut a slit at about right angles to the edge of the skived part of the leather and extending inward about one-eighth of an inch; a mechanism whereupon said slitting device may be vibrated; a device against which the cutting edge of said slitting device is vibrated in cutting said slit; a thick, recessed, beveled, disk-shaped device adapted to fold, press and rub leather; a bending device adapted to bend the skived part of the leather and press it down upon a recessed portion of the operative part of said folding, pressing and rubbing device; a mechanism whereupon said bending device may be vibrated; means whereupon said folding, pressing and rubbing device may be rotated and the operative part of said device thereby carried in a direction inward from the edge of the skived part of the leather, at about right angles to said edge, thereby folding, pressing and rubbing said leather; a presser against which said leather is held while it is pressed and rubbed by said folding, pressing and rubbing device; means whereupon said presser is yieldingly supported.

17. The following combination of instrumentalities, viz: a feeding device adapted to move a piece of leather; a mechanism whereupon said feeding device may be actuated; a presser-foot or device secured near to said feeding device; a rotatory disk skiving-knife

18. The following combination of instrumentalities, viz: a feeding device adapted to move a piece of leather; a mechanism whereupon said feeding device may be actuated; a presser-foot or device secured near to said feeding device; a rotatory disk skiving-knife and a knife-shaft secured thereto; an adjustable knife-shaft support for rotatably supporting said knife-shaft; means whereupon said adjustable knife-shaft support may be moved and secured in another position; a mechanism whereupon said rotatory disk skiving-knife may be actuated; a slitting device or shear-blade adapted to cut a slit at about right angles to the edge of the skived part of the leather and extending inward about one-eighth of an inch; a mechanism whereupon said slitting device may be vibrated; a device against which the cutting edge of said slitting device is vibrated in cutting said slit; a thick, recessed, beveled, disk-shaped device adapted to fold, press and rub leather; a cement-receptacle; a wheel or cement-carrying device movably supported in said cement-receptacle and extending out through said cement-receptacle; means whereupon said wheel or cement-carrying device may be mechanically moved whereupon a specific amount of cement is carried out of said cement-receptacle by said wheel or cement-carrying device; a brush or device adapted to take cement from the wheel or cement-carrying device and deposit the cement upon a recessed surface of a device for depositing cement upon a piece of leather and

and a knife-shaft secured thereto; an adjustable knife-shaft support for rotatably supporting said knife-shaft; means whereupon said adjustable knife-shaft support may be moved and secured in another position; a mechanism whereupon said rotatory disk skiving-knife may be actuated; a slitting device adapted to cut a slit at about right angles to the edge of the skived part of the leather and extending inward about one-eighth of an inch; a mechanism whereupon said slitting device may be vibrated; a device against which the cutting edge of said slitting device is vibrated in cutting said slit; a thick, recessed, beveled, disk-shaped device adapted to fold, press and rub leather; a bending device adapted to bend the skived part of the leather and press it down upon a recessed portion of the operative part of said folding, pressing and rubbing device; a mechanism whereupon said bending device may be vibrated; means whereupon said folding, pressing and rubbing device may be rotated and the operative part of said device thereby carried in a direction inward from the edge of the skived part of the leather, at about right angles to said edge, thereby folding, pressing and rubbing said leather; a presser against which said leather is held while it is pressed and rubbed by said folding, pressing and rubbing device; means whereupon said presser is yieldingly supported.

19. The following combination of instrumentalities, viz: a feeding device adapted to move a piece of leather; a mechanism whereupon said feeding device may be actuated; a presser-foot or device secured near to said feeding device; a rotatory disk skiving-knife and a knife-shaft secured thereto; an adjustable knife-shaft support for rotatably supporting said knife-shaft; means whereupon said adjustable knife-shaft support may be moved and secured in another position; a mechanism whereupon said rotatory disk skiving-knife may be actuated; a slitting device or shear-blade adapted to cut a slit at about right angles to the edge of the skived part of the leather and extending inward about one-eighth of an inch; a mechanism whereupon said slitting device may be vibrated; a device against which the cutting edge of said slitting device is vibrated in cutting said slit; a thick, recessed, beveled, disk-shaped device adapted to fold, press and rub leather; a cement-receptacle; a wheel or cement-carrying device movably supported in said cement-receptacle and extending out through said cement-receptacle; means whereupon said wheel or cement-carrying device may be mechanically moved whereupon a specific amount of cement is carried out of said cement-receptacle by said wheel or cement-carrying device; a brush or device adapted to take cement from the wheel or cement-carrying device and deposit the cement upon a recessed surface of a device for depositing cement upon a piece of leather and

also for folding, pressing and rubbing said leather; means whereupon said brush or device may be mechanically operated; a bending device adapted to bend the skived part 5 of the leather and press it down upon a recessed portion of the operative part of said folding, pressing and rubbing device; a mechanism whereupon said bending device may be vibrated; means whereupon said folding, 10 pressing and rubbing device may be rotated and the operative part of said device thereby carried in a direction inward from the edge of the skived part of the leather, at about right angles to said edge, thereby rubbing cement upon said skived part of the leather 15 and folding, pressing and rubbing said leather; a presser against which said leather is held while it is pressed and rubbed by said folding, pressing and rubbing device; means whereupon said presser is yieldingly supported. 20
